UNITED STATES PATENT OFFICE

134,759

DESIGN FOR A MILKING TIMER

Edwin J. Gengler, Milwaukee, Wis., assignor to
Paul J. Coleman, Highland Park, Ill.

Application May 21, 1942, Serial No. 106,970

Term of patent 14 years

To all whom it may concern:

Be it known that I, Edwin J. Gengler, a citizen of the United States, residing at Milwaukee, in the county of Milwaukee and State of Wisconsin, have invented a new, original, and ornamental Design for a Milking Timer, of which the following is a specification, reference being had to the accompanying drawing forming part thereof.

Fig. 1 is a front elevational view of a milking

timer, showing my new design, markings and numerals shown in Figs. 2 and 3 being merely representative;

Fig. 2 is a side elevational view; and
Fig. 3 is a top plan view.

I claim:

The ornamental design for a milking timer, as shown and described.

EDWIN J. GENGLER.
